UNITED STATES PATENT OFFICE.

ALBERT H. SISSON, OF CHICAGO, ILLINOIS, ASSIGNOR TO FORSYTH BROTHERS COMPANY, OF CHICAGO, ILLINOIS, A CORPORATION OF ILLINOIS.

SIDE-POST CONSTRUCTION FOR CARS.

1,112,857.

Specification of Letters Patent.

Patented Oct. 6, 1914.

Application filed June 28, 1912. Serial No. 706,837.

To all whom it may concern:

Be it known that I, ALBERT H. SISSON, a citizen of the United States, residing at Chicago, in the county of Cook and State of Illinois, have invented certain new and useful Improvements in Side-Post Construction for Cars, of which the following is a specification.

This invention has to do primarily with 10 side post construction for steel railway cars although adapted also to the steel framing of sheet metal structures of other sorts.

The object of the invention is to provide a 15 side post which shall constitute a rigid vertical support between window openings and a firm point of attachment for the sheathing including the letter board of the car, which can be constructed without waste of material and at a low cost of manufacture by reason 20 of the few operations required.

The invention reaches also to the attachment between the side posts and the sheathing whereby the window frame is provided in a simple and efficient manner to produce 25 a harmonious effect.

In the accompanying drawings wherein 30 corresponding reference numerals indicate similar parts throughout, I have illustrated by way of example one preferred embodiment of the invention.

In these drawings Figure 1 is a side elevation of a portion of the side framing of a car constructed according to the invention; Fig. 2 is a detail perspective view upon an 35 enlarged scale showing the connection between the window post and the upper sheathing or letter board of the car; and Fig. 3 is a similar view showing the connection between the lower sheathing, the window post and window sill. Fig. 4 is a fragmentary detail perspective view of a window post embodying the features of the 40 present invention. Fig. 5 is an enlarged detail sectional view taken on the line 5—5 45 Fig. 1.

In the drawings reference numeral 11 designates the lower sheathing of the car side while 12 designates the upper sheathing, or, as it is more commonly called, the letter 50 board. Supported below by the side sill and above by the side plate, neither of which is shown, is the side post 13 formed in the present case of sheet steel by bending a sheet of the same longitudinally at 14 and 55 15 to form a channel having upper and

lower transverse slits *a* and *b*. These slits are spaced at intervals corresponding to the upper and lower margins of the window openings. The channel portions above the upper pair of slits *a* are then bent outwardly 60 to form wing flanges 16 and 17 with their front faces lying in a common plane back of the front face of the post while the channel portions below the lower pair of slits *b* are also bent outwardly to form similar wing 65 flanges 18 and 19. The channel portions intermediate the two pairs of slits are bent inwardly toward each other as shown at 20 and 21 and meet to close the front of the channel and constitute thereof a tubular 70 portion 23.

The plane of the outer faces of the members 16, 17, 18 and 19 is disposed back of the post portions 20 and 21 a distance corresponding to the thickness of the sheet metal 75 sheathing so that when the upper sheathing 12 is placed upon the wing flanges 16 and 17 and secured thereto by means of the rivets 24 and when the lower sheathing 11 is placed upon the wing flanges 18 and 19 and secured 80 thereto by the rivets 25, the front face of the tubular portion of the post will occupy a plane flush with that of the sheathing.

The upper sheathing or letter board 12 is cut away at 26 to provide a notch corresponding in width to that of the tubular portion of the post and is marginally bent inward as shown at 27 to give an upper finish to the window opening while the sheathing 11 is likewise notched at 28 for a width corresponding to that of the tubular portion of the post and bent inwardly above the upper ends of the flanges 18 and 19 and alongside the post to form the window sill or sash rest 29. Upon each of the sides of the posts between the sill 29 and the upper margin of the window opening is suitably secured the sash guide strip 30.

The meeting edges of the inwardly bent facing portions 20 and 21 are preferably 100 welded together to form a substantially integral structure while the line of junction 28 between the sill and the tubular post may likewise be joined by welding or any other suitable manner.

It will be readily appreciated that the 105 structure described is a very economic one from the standpoint of manufacture and material while it possesses in a high degree the requisite characteristics of stability and 110

neatness and efficiency for the purposes intended.

I claim—

1. In a side post construction, a sheet metal channel provided with a pair of marginal alined slits, the margins on one side of the pair of slits bent inwardly toward each other to form a tubular portion and on the other side of the pair of slits bent outwardly to form a channel portion with wing flanges, the tubular portion constituting a window post, and the sheathing overlying and secured to the flanged channel portion, substantially as described.

2. In a side post construction, a sheet metal channel provided with a pair of marginal alined slits, the margins on one side of the pair of slits bent inwardly toward each other to form a tubular portion and on the other side of the pair of slits bent outwardly to form a channel portion with wing flanges, the tubular portion constituting a window post, and sheathing overlying and secured to the flanged channel portion and inwardly bent over the flanges in line with the slits and alongside the post to form a window sill, substantially as described.

3. In a side post construction, a sheet metal channel provided with spaced pairs of marginal alined slits, the margins of the channel between two pairs of slits bent inwardly toward each other to form a tubular intermediate portion and on the other sides of the two pairs of slits bent outwardly to form a channel portion with wing flanges, the tubular portion constituting a post between adjacent window openings, and the sheathing overlying and secured to the flanged channel portions, substantially as described.

4. In a side post construction, a sheet metal channel provided with spaced pairs of marginal alined slits, the margins of the channel between two pairs of slits bent inwardly toward each other to form a tubular intermediate portion and on the other sides of the two pairs of slits bent outwardly to form a channel portion with wing flanges, the tubular portion constituting a post between adjacent window openings, the sheathing overlying and secured to the flanged channel portions, and inwardly bent over the lower flanges in line with the slits and alongside the posts to form window sills, substantially as described.

5. In a side post construction, a sheet metal channel provided with spaced pairs of marginal alined slits, the margins of the channel between the two pairs of slits bent inwardly toward each other and welded together to form a tubular portion, the margins of the channel beyond the tubular portion bent outwardly to form a channel portion with wing flanges occupying a plane

slightly to the rear of the front face of the tubular portion constituting a post supporting adjacent window openings, the sheathing overlying and secured to the flanged channel portions above and below the window openings, the upper sheathing notched and inwardly turned to form an upper marginal finish for the opening and the lower sheathing notched and inwardly bent over the wing flanges and alongside the post to 70 form a window sill, substantially as described.

6. The method of constructing a side framing for cars and other buildings, which consists in forming a metallic sheet into a 80 channel having alined marginal transverse slits arranged in pairs corresponding to the upper and lower edges of the window opening, bending the margins of that portion of the channel between the two pairs of slits 85 inwardly toward each other to form a tubular post separating adjacent window openings, bending the margins of those portions of the channel above and below the tubular portion outwardly to form wing flanges occupying a common plane, and securing the sheathing to the outer faces of the wing flanges above and below the tubular portion, 90 substantially as described.

7. The method of constructing a side 95 framing for cars and other buildings, which consists in forming a metallic sheet into a channel having alined marginal transverse slits arranged in pairs corresponding one to the upper and the other to the lower line of 100 the window opening, bending the margins of that portion of the channel between the pairs of slits inwardly toward each other, welding the meeting edges to form a tubular post between the window openings, bending 105 those portions of the channel above and below the tubular portion outwardly to form wing flanges occupying a common plane slightly to the rear of the front face of the tubular portion, securing the sheathing to the front faces of the wing flanges and bending the upper sheathing inwardly to 110 form an upper finish for the window opening and the lower sheathing inwardly alongside the tubular portion to form a window 115 sill, substantially as described.

8. The method of constructing a side framing for cars and other buildings, which consists in forming a metallic sheet into a channel having alined marginal transverse slits arranged in pairs corresponding one to the upper and the other to the lower line of the window opening, bending the margins of that portion of the channel between the pairs of slits inwardly toward each other, 125 welding the meeting edges to form a tubular post between the window openings, bending those portions of the channel above and below the tubular portion outwardly to form wing flanges occupying a common plane 130

slightly to the rear of the front face of the tubular portion, securing the sheathing to the front faces of the wing flanges and bending the upper sheathing inwardly to form an upper finish for the window opening and the lower sheathing inwardly alongside the tubular portion to form a window sill, and securing guide strips upon the sides of the

tubular portion between the inwardly bent portions of the upper and lower sheathing, 10 substantially as described.

ALBERT H. SISSON.
